UNITED STATES PATENT OFFICE.

CARRIE EDITH McMURRY, OF NASHVILLE, TENNESSEE.

CAMERA.

SPECIFICATION forming part of Letters Patent No. 553,494, dated January 21, 1896.

Application filed March 18, 1895. Serial No. 542,169. (No model.)

To all whom it may concern:

Be it known that I, CARRIE EDITH McMURRY, a citizen of the United States, residing at Nashville, in the county of Davidson 5 and State of Tennessee, have invented certain new and useful Improvements in Cameras; and I do hereby declare the following to be a full, clear, and exact description of the invention, such as will enable others skilled 10 in the art to which it appertains to make and use the same.

My invention relates to an improvement in cameras; and it consists in the construction and arrangement of parts hereinafter described, and definitely pointed out in the 15 claims.

The aim and purpose of the invention is the provision of an improved instrument whereby enlarged or reduced reproductions 20 of images or objects may be made, and in addition thereto to so construct the device that the same may be used for advertising purposes and for projecting images or objects onto a canvas.

25 A further object is the production of an instrument of the nature referred to which will embody structural simplicity, rendering its production inexpensive and one which may be easily operated.

30 These objects are attained by the construction illustrated in the accompanying drawings, wherein like letters of reference designate corresponding parts in the several views, and in which—

35 Figure 1 is a side view of the camera. Fig. 2 is a vertical section through Fig. 1 on the line xx . Fig. 3 is a rear view, and Fig. 4 is a slightly-modified form. Fig. 5 is a detail view of the table-adjusting means.

40 In the drawings, A designates a rectangular box having a top with a slightly-inclined part B and flat open part B'. The rear face of the box is formed in sections a , a' and a^2 , the former being at the base, while the sections a' 45 a^2 are hinged respectively to the lower section and together and are held in place by suitable hooks a^3 . In the section a' is formed an opening in which a lens C is placed. On top of the flat top portion B' is a swinging rectangular case D, hinged at its lower rear corner, as at d , to the box at a point slightly back from the edge. This case D is closed and has a

lens D' in its base and carries a telescopic or extensible bellows-tube E on its front face registering with an aperture which is located 55 diametrically opposite an inclined mirror C', secured in the box over the lens D'. The telescopic holder has a lens D² in its end.

Centrally within the box A is a vertically-adjustable table formed preferably of a mirror F, which is mounted on brackets f, carrying racks f', which mesh with pinions F' mounted in the sides of the box. The pinions are turned by suitable knobs f² extended to the outside of the box. The mirror or table 60 is tilted by being pivotally or otherwise mounted in the brackets, and when the desired angle is reached the same is locked by set-screws f³ or other suitable means.

G designates a slideway in line with a lens 70 g located in the front of the box. In this slideway suitable lantern-slides may be placed when the instrument is to be used as a magic lantern.

In operation the case D is turned up, as 75 shown in Fig. 1, its forward edge resting on a suitable flange d². The case thus forms a closure for the flat top or end. The telescopic lens-carrier is then adjusted, and the picture or object is thrown onto the mirror 80 in the casing D and from there through the lens D' onto the table, on which a suitable drawing-board may be placed. The lenses are arranged to reduce the size of the object projected therethrough. When it is desired 85 to enlarge a picture or object, a lamp, as at L, is placed back of the lens C, or the back section may be removed so that the rays of light will strike the picture or object lying on the table and being magnified by the lens D' will 90 be deflected by the mirror C' through the lens D² onto the canvas.

The use of the horizontal lens D' is of the utmost importance, as it serves to strengthen the outline and reflected image, so that when 95 the same is projected through the outer lens it will be strongly delineated in line and color onto the canvas. By adjusting the table the object may be properly focused relative to the lens, and this whether the instrument is 100 used in its obverse or reverse order.

When the light is required to be exceptionally strong the lens C is employed. When it is desired to make a reduced reproduction of an

object or picture the mirror or table is inclined so as to reflect the image through the lens C onto a canvas arranged opposite thereto.

In packing the instrument for transportation the case D is turned on its hinges until it is carried into the box, the case being of a length less than the box, the rear side of the case serving to close the open top, and as the back is adjusted the upper section a² will 10 hold the case in place.

When it is desired to employ the instrument as a magic lantern, the lamp, which is properly shaded, is placed below the opening in the top. The case D is swung back and 15 the mirror or table is tilted out of position. Slides are then placed in the slideway, and the picture on the slide is thrown onto the canvas in the usual manner.

When it is desired to employ the device for advertising purposes, a detachable bracket M is secured to the forward edge of the box, and an inclined mirror N is then secured at its outer end in front of the lens D². The image is thereby reflected onto the floor or walk.

25 The attractiveness of the instrument as an advertising means may be further amplified by having the mirror in the case D of concaved or convexed form and oblong.

I am aware that many minor changes can 30 be made and substituted for the parts herein shown and described without in the least departing from the nature and principle of my invention.

Having thus described my invention, what 35 I claim as new, and desire to secure by Letters Patent, is—

1. A camera, of the kind described consisting of a box having a removable back, a movable case on the upper end and rear of the 40 box, a lens at the base of the case, an inclined

mirror in the case, an independent horizontally adjustable holder on the front of the case, a lens in the holder, and a tilttable table below the case, substantially as described.

2. In a camera, the combination with a box 45 having a removable back, a lens in the back, and a table in the box, of a case hinged on the top of the box, a lens at the base of the case, an inclined mirror in the case, and a telescopic holder on the case having a lens 50 therein, substantially as described.

3. In a camera, the combination with a box, of a case on the box, a lens at the base of the case, a table in the box below the lens, a mirror in the case, a telescopic holder on the 55 case having a lens therein, and a mirror arranged in front of the holder, substantially as described.

4. A camera of the kind described, consisting of a box, a case on the box having a horizontal lens at its base and an inclined mirror, a removable back for the box, a lens in the back, and a vertically adjustable tilttable table below the lens in the case, substantially as described. 60

5. In a camera, the combination with a box having an open top, of a casing of a length less than the width of the box, a hinged connection between the rear of the casing and box, a lens at the base of the casing, an inclined mirror in the casing, an adjustable support below the lens, and a removable back 70 for closing the entire rear of the box, substantially as described.

In testimony whereof I affix my signature 75 in presence of two witnesses.

CARRIE EDITH McMURRY.
